INVENTOR

BY *Victor J. Evans*

ATTORNEY

UNITED STATES PATENT OFFICE.

FRANCIS M. MULLIGAN, OF BUTTE, MONTANA.

TOY.

Application filed February 11, 1922. Serial No. 535,824.

To all whom it may concern:

Be it known that I, FRANCIS M. MULLIGAN, a citizen of the United States, residing at Butte, in the county of Silver Bow and 5 State of Montana, have invented new and useful Improvements in Toys, of which the following is a specification.

This invention relates to a toy, the general object of the invention being to provide a 10 toy made to represent an animal and which is provided with a roller eccentrically mounted so that the toy will be given an up and down motion as it is moved along.

Another object of the invention is to provide the toy with movable legs which are so arranged that they will be moved back and forth by the up and down movement of the toy.

This invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote like or corresponding parts throughout the 30 several views, and in which:—

Figure 1 is a side view of the invention.

Figures 2 and 3 are detail views.

In these views 1 indicates the body of the toy which is preferably formed of a strip 35 of wood which is cut to represent an animal. The under part of the body is provided with a recess 2 to receive a roller 3. Metal plates 4 cover the ends of the recess and receive the ends of the pivot pin 5 of the roller, this pin 40 being eccentrically arranged in the roller. Legs 6 are pivoted to the body, as at 7, and the heel parts are connected together by means of the pin 8 which passes beneath the body, its object being to cause the two feet

to move together and to add weight to the 45 parts.

The body can be pulled along by a string or the like or it may be provided with a spring motor which is arranged to rotate the roller 3. As the toy moves along the floor 50 the roller revolves and its eccentric pivot pin will cause the roller to raise and lower the front part of the toy. The tail part of the body will slide upon the surface. As the body raises the legs will move forwardly 55 under the action of gravity and then when the body moves downwardly again the feet coming in contact with the floor will be moved backward, thus the feet will be given a walking motion.

Where the toy is made to represent an animal with four legs, two eccentrically arranged rollers would be used so as to give motion to both pairs of legs.

It is thought from the foregoing description that the advantages and novel features of my invention will be readily apparent.

I desire it to be understood that I may make changes in the construction and in the combination and arrangement of the several 70 parts, provided that such changes fall within the scope of the appended claim.

What I claim is:—

A toy comprising a body having a tail extending at one end which is adapted to engage the surface upon which the toy is placed, said body having a recess formed in its lower edge, an eccentrically arranged roller arranged in the recess for engaging the said surface, a leg pivotally secured to each side of the body above the roller and arranged to move downwardly and forwardly under the action of gravity as the body is raised by the roller and to be moved backwardly through engagement to the supporting surface when the body is lowered.

In testimony whereof I affix my signature.

FRANCIS M. MULLIGAN.
